UNITED STATES PATENT OFFICE.

JULIUS C. TORCHIA, OF HAZLETON, PENNSYLVANIA.

AUTOMATIC STARTING AND STOPPING MECHANISM FOR PHONOGRAHS.

1,389,169.

Specification of Letters Patent.

Patented Aug. 30, 1921.

Application filed June 9, 1920. Serial No. 387,655.

To all whom it may concern:

Be it known that I, JULIUS C. TORCHIA, a citizen of the United States, residing at Hazleton, in the county of Luzerne and State 5 of Pennsylvania, have invented certain new and useful Improvements in Automatic Starting and Stopping Mechanism for Phonographs, of which the following is a specification.

10 This invention relates to improvements in automatic starting and stopping mechanisms for sound reproducing apparatus and has as its general object to provide means actuated through the movement of the tone arm of 15 the apparatus to automatically release and to automatically set a brake member which coacts with the record supporting turntable so that when the tone arm is swung to position to start the stylus in the outer end portion of the record groove, the brake will be released, and when the arm reaches the inner end of its travel, the brake will be set thus stopping the rotation of the said turntable.

20 Another object of the invention is to provide a mechanism for the purpose stated which may be readily applied to practically any of the ordinary makes of phonographs and readily attached in place without any 25 appreciable alteration of the phonograph itself.

Another object of the invention is to construct the tripping member of the mechanism so that the same may be readily adjusted to adapt the mechanism for application to various types of machines.

In the accompanying drawings:

Figure 1 is a plan view of the mechanism embodying the present invention, the view 40 illustrating the mechanism in its operative relation to certain parts of a phonograph and which parts are illustrated partly in dotted lines;

Fig. 2 is a similar view but showing the 45 relative positions assumed by the parts of the mechanism when the brake is set or active;

Fig. 3 is a detail perspective view illustrating the mechanism detached, the view 50 also illustrating a portion of the tone arm and a portion of the record supporting turntable.

In the drawings the numeral 1 indicates in general the tone arm of the phonograph, 2 55 the sound box carried at the forward end of this arm, and 3 the record supporting turn-

table which is provided upon its under side with the usual peripheral depending flange 4 with which flange the brake element of the mechanism embodying the present invention is designed to coact. The mechanism of the invention is substantially completely housed beneath the turntable 3 and the same comprises a base plate 5 which is designed to be secured to the upper surface 60 of the top board or table of the phonograph. The mechanism includes a brake member which is indicated in general by the numeral 6 and this member comprises a head 7 which is mounted by means of a pivot 8 upon the base plate 5 near one end of the latter. An arm 9 projects from the periphery of the head 7 and has an upwardly directed end 10 which carries a small brake shoe 11 designed for coaction with the inner side of 70 the flange 4, the said shoe being brought into and out of engagement with the flange by turning movement of the head 7 upon its pivot 8.

In order to hold the head 7 in such position as to maintain the brake shoe 11 in inactive position, a detent member is provided and this member is indicated in general by the numeral 12 and comprises an arm 13 which is pivotally mounted as at 14 upon the base plate 5 near the opposite end of the latter. At its free end the said detent arm 13 is provided with a laterally projecting tooth 15 engageable in a notch 16 formed in the periphery of the head 7, and when the tooth 16 is engaged in the notch the head 7 will be in such position of rotation that the brake shoe 11 will be held clear of the flange 4 of the record supporting turntable as clearly shown in Figs. 1 and 2 of the drawings. In order 95 to effect automatic movement of the brake member to active position when released by the detent 12, and to yieldably hold the brake shoe in engagement with the flange 4, a coiled spring 17 is connected at one end to an 100 upstanding finger 18 upon the head 7 of the brake member 6 and at its other end to a similar finger 19 upon the detent arm 13.

Not only does the spring 17 tend to rotate the brake member to active position but it 105 also exerts a pull upon the detent arm 13 tending to swing the outer end of the said arm inwardly toward the periphery of the head 7 of the brake member when the brake member is in or rotated to inactive position, and on the other hand tends to swing the said 110 detent arm 13 in the opposite direction when

the brake member is in or swung to active position. Thus as the brake member 16 is rotated to inactive position, the arm 13 will be automatically swung inwardly so that its 5 tooth 15 will engage in the notch 16 and retain the member in inactive position when this position is reached, notwithstanding the pull exerted thereon by the spring 17. On the other hand upon initial movement of the 10 head 17 to cause the brake member to assume an active position, the direction of pull of the spring upon the arm 13 will be changed so that the arm will then tend to swing outwardly to cause the tooth 15 to clear said 15 notch 16. The numeral 20 indicates an arm which projects from the periphery of the head 7 beneath the lower edge of the flange 4, and beyond the periphery of the record supporting turntable.

20 Mounted upon the pivot 14 for rocking movement, is a tripping member which is indicated in general by the numeral 21 and this tripping member comprises arms 22 and 23 which extend in diverging relation and 25 the former of which is formed near its outer end with a longitudinally extending slot 24 receiving a pin 25 carried at the outer end of the arm 20. It will be evident at this point that rocking movement of the member 21 and 30 consequently of its arm 22 will result in rocking movement of the arm 20 and consequently in rotation of the head 7 of the brake member 6.

The arm 23 supports a tripping member 35 which is indicated in general by the numeral 26, and this member is mounted upon the arm by means of a screw 27 which is fitted through the member near its inner end and threaded into the end of the arm 23. A friction disk 28 is disposed upon the screw 27 between the under side of the said member 26 and the upper side of the arm 23 and it will therefore be evident that by loosening the screw 27, the member 26 may be angularly 40 adjusted with relation to the arm 23 and that by again tightening the screw the member will be secured in its position of adjustment. In order to provide for accurate adjustment of the member and to insure against 45 its accidental displacement under working conditions after it has been adjusted to the proper angular position with relation to the arm 23, a set screw 29 is adjustably threaded through an upstanding ear 30 upon the said arm 23 at one side thereof and bears at its 50 inner end against one lateral edge of the rear end portion of the member 26. This member 26 is provided at its outer end with two fingers one indicated by the numeral 31 and the other by the numeral 32. The fingers extend 55 along relatively diverging lines, and the one indicated by the numeral 32 has one of its edges of cam formation as indicated by the numeral 33 and is provided with an extension 34 designed to project beyond the per-

iphery of the turntable 3 as clearly shown in Figs. 1 and 2 of the drawing and may be provided with a finger knob 35 to permit of the member 26 being swung, and inasmuch as this member is rigidly held connected with 70 the arm 23, such swinging movement will, of course, be imparted to this arm and consequently to the arm 22. The member 26 is also provided with a finger 36 which is supplemental to the finger 31. This finger 36 is 75 mounted upon the member 26 at the inner end of the finger 31 by means of a set screw 37 fitted through the inner end of the said member 26, a friction disk or washer 38 being interposed between the said inner end of the finger 36 and the upper surface of the said member 26 so that by loosening the set screw 37 the finger 36 may be angularly adjusted and by 80 tightening the set screw the finger may be held in its position of adjustment. The tone arm 1 is provided upon its under side near its inner end with a downwardly projecting pin which is indicated by the numeral 39 and which coacts with the trip member 26 in a 85 manner which will now be described.

In applying the mechanism to a selected sound reproducing apparatus, the base plate 5 is secured to the top board of the box or cabinet of the apparatus in such position 95 that when the parts of the device are as shown in Fig. 2, the brake shoe 11 will be in firm engagement with the depending flange 4 of the record turntable, and when the parts are in the position shown in Fig. 1, the brake shoe will be out of such engagement. Also the device is so positioned that the fingers 31, 32 and 36 will be in the path of movement of the pin 39 in the swinging movement 100 of the tone arm.

In Fig. 2 of the drawings the parts of the mechanism are in such position that the brake is active and consequently in engagement with the flange of the turntable. In this position of the parts the pin 39 is located in the angle between the fingers 31 and 32 and behind the cam 33 of the latter finger. After the record has been placed upon the turntable it is only necessary, in order to start the machine, to swing the tone arm 110 to the right so as to position the stylus in the outer end portion of the record groove. When the tone arm is thus moved, the pin 39 will ride against the cam portion 33 of the arm 32 thus effecting angular movement 115 of the member 26 and consequently of the arm 22. As this arm is swung, swinging movement will be imparted to the arm 20 and consequently the head 7 will be rotated and it finally assumes about the position 120 shown in Fig. 1 of the drawings in which position the arm 13 will have been moved inwardly through the influence of the spring 17 so as to bring the tooth 15 into engagement in the notch 16 and in this manner the 125 130

detent arm 13 will restrain the brake member 6 against movement to active position. In the playing of the record, the tone arm 1 will be carried inwardly in the usual manner as the stylus travels in the record groove, until finally the pin 38 will come into engagement with the finger 31. Upon such engagement of the pin against the finger, the member 26 will be slightly rocked about its pivot and this motion will be transmitted to the arm 22 and to the brake member 6. In the inactive position of the brake, the spring 17 extends between the fingers 18 and 19 along a line passing directly above the tooth 15 which is at such time engaged within the notch 16 but upon slight movement of the brake member about its pivot caused through the movement of the arm 22 under the conditions above stated, the position of the spring 20 will be slightly shifted so that the detent member 12 will be swung out of active position and the spring will then immediately act to swing the brake member 6 so as to bring its shoe member 11 into braking engagement with the flange of the record turntable. In the manufacture of the device, the fingers 31 and 32 may be suitably relatively positioned to adapt the device for application to a sound reproducing machine of a 25 certain definite type and make and likewise to suit records of a certain definite size but where records of another size are to be employed and where the record grooves thereof would terminate a distance from the center 30 of the record greater than that which would provide for the tone arm being carried inwardly to bring the pin 39 into engagement with the finger 31, the finger 36 may be brought into use and angularly adjusted so 35 that it will be engaged by the said pin 39 substantially at the moment the stylus upon the tone arm reaches the inner end of the groove in the particular type of record to be employed. Likewise a supplemental adjustment may be effected by adjusting the 40 set screw 29.

Having thus described the invention, what is claimed as new is:

1. In automatic starting and stopping mechanism for phonographs controlled through the movement of the tone arm, a brake member, a tripping member mounted for oscillatory movement and connected with the brake member, means tending to move the brake member to active position, a detent for holding the brake member in inactive position and adapted to be rendered inactive upon movement of the tripping member in one direction, and an actuating element for movement with the tone arm and for coaction with the tripping member.

2. In automatic starting and stopping mechanism for phonographs controlled through the movement of the tone arm, a 55 brake member, a tripping member mounted

for oscillatory movement and connected with the brake member, means tending to move the brake member to active position, a detent for holding the brake member in active position and adapted to be rendered inactive upon movement of the tripping member in one direction, and an actuating element for movement with the tone arm and for coaction with the tripping member, the said tripping member having spaced fingers 70 one engageable by the said actuating element when the tone arm is moved in one direction to effect actuation of the tripping member to render the brake member active and the other engageable by the said actuating element to effect movement of the tripping member to render the brake member inactive.

3. In automatic starting and stopping mechanism for phonographs controlled 85 through the movement of the tone arm, a brake member, a tripping member mounted for oscillatory movement and connected with the brake member, means tending to move the brake member to active position, a detent for holding the brake member in inactive position and adapted to be rendered inactive upon movement of the tripping member in one direction, an actuating member 90 for movement with the tone arm and for coaction with the tripping member, the said tripping member having spaced fingers one engageable by the said actuating element when the tone arm is moved in one direction to effect actuation of the tripping member to render the brake member active and the other engageable by the said actuating element to effect movement of the tripping member to render the brake member inactive, and means whereby the fingers may be 95 angularly adjusted.

4. In automatic starting and stopping mechanism for phonographs controlled through the movement of the tone arm, a brake member, a tripping member mounted for oscillatory movement and connected with the brake member, means tending to move the brake member to active position, a detent for holding the brake member in inactive position and adapted to be rendered 110 inactive upon movement of the tripping member in one direction, a member mounted for angular adjustment upon the tripping member and having spaced abutment fingers, and an actuating element for movement with the tone arm and for coaction with the said fingers.

5. In automatic starting and stopping mechanism for phonographs controlled through the movement of the tone arm, a 115 brake member, a tripping member mounted for oscillatory movement and connected with the brake member, means tending to move the brake member to active position, a detent for holding the brake member in in- 120 125 130

active position and adapted to be rendered inactive upon movement of the tripping member in one direction, the tripping means comprising an angularly adjustable member having spaced rigidly connected fingers one provided with a cam portion, and an actuating element for movement with the tone arm and for coaction with the said cam portion of said finger to move the tripping member in a manner to render the brake member inactive and for coaction with the other finger to render the detent member inactive and release the brake member for movement to active position.

6. In automatic starting and stopping mechanism for phonographs controlled through the movement of the tone arm, a brake member, a tripping member mounted for oscillatory movement and connected with the brake member, means tending to move the brake member to active position, a detent for holding the brake member in inac-

tive position and adapted to be rendered inactive upon movement of the tripping member in one direction, the tripping means comprising an angularly adjustable member having spaced rigidly connected fingers one provided with a cam portion, an actuating element for movement with the tone arm and for coaction with the said cam portion of said finger to move the tripping member in a manner to render the brake member inactive and for coaction with the other finger to render the detent member inactive and release the brake member for movement to active position, and a supplemental finger angularly adjustably mounted upon the tripping member and adjustable to position to be engaged by the actuating element in preference to engagement of the said element with one of the first-mentioned fingers.

In testimony whereof I affix my signature.

JULIUS C. TORCHIA. [L.S.]
